DESIGN FOR A SELF-CLOSING REFUSE CAN TOP

Kenneth N. Perkins, Cincinnati, Ohio, assignor to
The F. H. Lawson Company, Cincinnati, Ohio,
a corporation of Ohio

Application March 25, 1940, Serial No. 91,227

Term of patent 14 years

To all whom it may concern:

Be it known that I, Kenneth N. Perkins, a citizen of the United States, residing in Cincinnati, county of Hamilton, and State of Ohio, have invented a new, original, and ornamental Design for Self-Closing Refuse Can Top, of which the following is a specification, reference being had to the accompanying drawing, forming part thereof.

In the drawing,

Fig. 1 is a perspective view of a can top showing my new design.

Fig. 2 is a transverse sectional view of the can top shown in Fig. 1, taken on the plane of the dot-dash circle of Fig. 1 and looking in the direction of the arrows.

Fig. 3 is a side elevational view of the can top shown in Fig. 1.

I claim:

The ornamental design for a self-closing refuse can top, as shown.

KENNETH N. PERKINS.
